COMBINED BOOKRACK AND FLOOR LAMP

Jeanette James, Chicago, Ill.

Application May 23, 1952, Serial No. 19,866

Term of patent 7 years

(Cl. D48—20)

To all whom it may concern:

Be it known that I, Jeanette James, a citizen of the United States, residing at Chicago, in the county of Cook and State of Illinois, have invented a new, original, and ornamental Design for a Combined Book Rack and Floor Lamp, of which the following is a specification, reference being had to the accompanying drawing, forming a part hereof.

Fig. 1 is a side elevational view of a combined book rack and floor lamp, showing my new design;

Fig. 2 is a cross sectional view thereof taken on the line 2—2 of Fig. 1; and

Fig. 3 is a fragmentary cross sectional view taken on the line 3—3 of Fig. 2.

I claim:

The ornamental design for a combined book rack and floor lamp, as shown.

JEANETTE JAMES.
